CLAIM

The ornamental design for an attachment for the trailing end of a urethral drainage tube, as shown and described.

DESCRIPTION

FIG. 1 is a perspective view of an attachment for the trailing end of a urethral drainage tube showing my new design;

FIG. 2 is a top plan view thereof;

FIG. 3 is a side elevational view thereof;

FIG. 4 is an end elevational view thereof;

FIG. 5 is an end elevational view thereof, opposite that shown in FIG. 4;

FIG. 6 is a perspective view thereof;

FIG. 7 is a top plan view thereof;

FIG. 8 is an end elevational view thereof;

FIG. 9 is an end elevational view thereof, opposite that shown in FIG. 9;

FIG. 10 is a side elevational view thereof; and,

FIG. 11 is a side elevational view thereof, opposite that shown in FIG. 10.

The broken line showing in FIGS. 6, 7 and 9 through 11 of a drainage tube is for illustrative purposes only and forms no part of the claimed design.
